UNITED STATES PATENT OFFICE.

MONROE H. DANIELS, OF WAVERLY, IOWA.

MILKING-MACHINE.

No. 908,449.

Specification of Letters Patent.

Patented Jan. 5, 1909.

Application filed May 22, 1908. Serial No. 434,313.

To all whom it may concern:

Be it known that I, MONROE H. DANIELS, a citizen of the United States of America, and a resident of Waverly, Bremer county, Iowa, have invented certain new and useful Improvements in Milking-Machines, of which the following is a specification.

My invention relates to improvements in milking-machines, particularly to that form which employs a pulsator intermediately between the teat-cups and the milk-receptacle, and the objects of my improvements are these: First, to provide an improved form of pulsator constructed for the milking of two cows independently of each other. Second, to actuate said pulsator by independent mechanical means adapted to exercise sufficient direct force thereon to prevent cessation of motion thereof on account of adhesiveness under certain conditions of temperature. Third, to furnish an auxiliary device for automatically shutting off the vacuum-connection at desired times. These objects I have accomplished by the mechanism and means which are hereinafter fully described and claimed, and which are illustrated in the accompanying drawings, in which:

Figure 1 is an elevation of my said improved milking-machine, certain connections being broken away. Fig. 2 is an upper plan of same. Fig. 3 is a vertical section of same taken on the line *a*—*b* of Fig. 2. Fig. 4 is a horizontal section of the pulsator taken on the line *c*—*d* of Fig. 3.

Similar numbers refer to similar parts throughout the several views.

The circular plate 23 has a rabbeted edge adapted to fit the upper edge of a milk-receptacle 38. The plate 23 is centrally orificed, such orifice being interiorly threaded to receive therethrough an exteriorly-threaded bushing or cylinder 14, an annulus 29 integral therewith resting upon the top of said plate. On opposite sides of the annulus 29 are projections 30, such projections and the cylinder being both orificed in line from the exterior of the projections to communicate with the inner bore of the cylinder, and tubes 25 being screwed into said orifices and leading to suitable teat-cups (not shown).

Within and fitting the axial bore of the cylinder 14 is a plunger 31 whose upper end has a flange 12 adapted to contact removably with the upper end of said cylinder. Opposite sides of the plunger 31 have recesses 32 extending most of the way from the

lower to the upper part thereof. Radial openings 13 on opposite sides of the cylinder 14 afford at certain times communication respectively with the recesses 32 adjacent thereto in the plunger and the atmosphere, while other radial openings 34 near the base of the cylinder afford communication respectively between such recesses and the interior of a milk receptacle under said plate 23, at certain times.

The projections 30 on the cylinder 14 are also perforated vertically intersecting the horizontal channels 33, and in such vertical perforations plungers 16 are respectively seated. Each plunger 16 has a transverse orifice 37 which is adapted to be placed in occasional communication with the transverse channel 33 by means to be hereinafter described. The top of each plunger 16 has a pivotal connection with the inner end of a lever 17 on a pivot-bolt 15. Each lever 17 is medially pivoted to the top of an upright 21 on a pivot-bolt 18. A weight 22 is seated slidably and removably on the free outer end of each lever 17, and may be secured in an adjusted position thereon by a set-screw 20. A cross-bar 35 is removably secured to the lower end of each plunger 16 by means of a screw 36, and the ends of such cross-bars 35 are secured to and support the conical vessels 27 open at the top and whose truncated lower ends are supplied with small drainage tubes 28 respectively.

The numeral 24 designates an electro-magnet whose cross-bar 3 has a bail 5 secured thereto by screws 4. The bail 5 is suspended with said magnet from the outer end of a lever 7 which is medially pivoted at 8 on the top of an upright 9. The inner end of said lever is pivoted to a bifurcated stud 11 on the top of the plunger 31 on a pivot-rod 10. The weight of the suspended electro-magnet 24 is equal to the weight of the plunger 31 and they thus balance each other, except at such times as a current derived from any source of electric power is sent through said electro-magnet, when the poles of the magnet will be attracted by and will advance toward the plate 23 thus elevating said plunger 31 in its seat. When the current is shut off, the magnet ascends and the plunger falls to its former balanced position. Any desired and suitable means may be employed with which to regularly and successively make and break the circuit through said electro-magnet to cause the latter to reciprocate and move the

plunger up and down past the ports to vary the amount of vacuum tension in the machine. Instead of an electrically-controlled means for reciprocating said plunger, however, other suitable means may be employed without departing from the scope of my invention which is the actuating of the plunger by means independent of the means used to exhaust the air from the teat-cups of said machine. This independent action is necessary, to prevent sticking of the plunger in its seat, which may easily occur when the parts are moistened with milk under a low temperature. My device is therefore entirely independent of temperature conditions, since as much power may be applied to the plunger as necessary without regard to the amount of pressure of the vacuum in the machine.

It will be observed that my machine is designed for the milking of two cows simultaneously, without a direct communication from one milk-tube 25 to the other through the plunger 31. Since the regulating means is independent for each cow from the regulating means for the other cow, a saving of power is effected, since the device is automatically shut off for each cow independently of the other when all milk has been stripped therefrom. This independently arranged regulating or cut-off means is described as follows.

When the teat-cups have been attached, and the vacuum-pump has exhausted the air from the communicating passages in the tube 19, the receptacle secured below the plate 23, the radial channels 34, the recesses 32, the registering channels 33, 37 and the passages in the tubes 25 communicating with the teat-cups, and the vacuum being at a proper pressure, milk is drawn through the passages leading from such teat-cups to the said receptacle. The weights 22 should be removed from the levers 17 first, however, to permit the weight of the vessels 27 to draw down the plungers 16 so that the channels 33 and 37 may register, and such weights not replaced until the said vessels are at least partially filled with milk from the channels 34. The weights being replaced, the apparatus is in working condition.

When the machine has been thus set to begin milking, the auxiliary means for actuating the plunger 31 is put in motion to impart to said plunger a regular and constant reciprocation. As the plunger 31 ascends it cuts off the channels 34 before the upper ends of the recesses 32 are placed in communication with the other radial channels 13. While the vacuum is thus preserved in the milk-pail, air under ordinary atmospheric pressure rushes into the channels and passages 13, 32, 33, 37 and the conduits 25 to the teat-cups, thus considerably lowering the vacuum pressure in the teat-cups during the short interval of time which elapses while the plunger is being moved up and down past said channels

13, thus successfully simulating the varying draft of a calf's suction. When the plunger moves down to its first position, the former degree of vacuum is gradually restored to the teat-cups. The milk flows constantly into the vessels 27 and overflows thereover into the receptacle below, until one or the other udder is exhausted of milk. When milk ceases to flow into one of the vessels 27, the milk remaining therein slowly drains therefrom by way of the tube 28. When the vessel 27 is emptied, the weight 22 which is set to overbalance the connected parts on the other side of the fulcrum, causes such parts including the plunger 16 to ascend to a position where the channel 33 is cut off by said plunger from communication with the vacuum-pump as shown in Fig. 3. Each plunger 16 is thus automatically-actuated independently from the other plunger 16, and the vacuum-pump is cut-off from the teat-cups where the milk has ceased to flow. Thus either side may be shut-off without interfering with the action of the other, and one cow may be milked alone if desired.

I have constructed my improved machine in such a manner that it may be easily flushed when its parts have been separated. The plungers 31 and 16 are easily disconnected from the levers 7 and 17 respectively, leaving all the cylindrical channels open and free of obstruction for rapid cleansing.

Having described my invention, what I claim as new, and desire to secure by Letters Patent, is:

1. In a milking machine, in combination, a milk-receptacle, means for exhausting the same, a pulsator having an upright valve-cylinder which opens at its lower end into said receptacle, a pulsator-valve arranged to move up and down in said cylinder, and means independent of the said air-exhausting means for moving said valve upwardly.

2. In a milking machine, in combination, a milk-receptacle, means for exhausting the same, a pulsator having an upright valve-cylinder, a pulsator-valve arranged to move up or down in said cylinder, said valve having separated recesses on opposite sides, said cylinder having a channel on each side in communication between the air-exhausting means and the adjacent recess in said valve, said cylinder also having channels in communication with the atmosphere and with the interior of said receptacle respectively and each adapted for occasional communication with the adjacent recess in said valve when the valve is moved longitudinally through said cylinder, and means for reciprocating said valve in said cylinder.

3. In a milking-machine, in combination, a milk-receptacle, means for exhausting the same, a pulsator having an upright valve-cylinder, a pulsator-valve arranged to reciprocate in said cylinder, said valve being pro-

vided with recesses, said cylinder being provided with a milk-port, an air-exhaust port and an air-inlet port, all adapted for occasional communication with said recesses, 5 said air-exhaust port opening into said receptacle, and means independent of the said air-exhausting means for causing the said pulsator-valve to move up or down in said cylinder.

10 4. In a milking-machine, in combination, a milk-receptacle, means for exhausting the same, a pulsator-casing having milk-ports, air-exhaust ports and air-inlet ports on opposite sides independent and separated 15 from each other, a pulsator-valve in said casing having a channel on each side separated from each other, each of said channels adapted for occasional communication with the said ports on the same side, means 20 independent of the said air-exhausting means for moving said valve to and fro past said ports, and means independent of said air-exhausting means for closing either of said milk-ports when milk has ceased to flow 25 therethrough.

5. In a milking machine, in combination, a milk-receptacle, means for exhausting the same, a pulsator-cylinder having an air-inlet port, an air-exhaust port and a milk-port, a 30 movable valve in said cylinder having a channel adapted for occasional communication with said air-inlet and said air-exhaust ports and for permanent communication with said milk-port, a valve adapted to close 35 said milk-port, and means adapted to move said valve to close said milk-port when the milk ceases to flow through said milk-port.

6. In a milking machine, in combination, a milk-receptacle, means for exhausting the 40 same, a pulsator-cylinder having an air-inlet port, an air-exhaust port and a milk-port, a pulsator-valve movable within said cylinder and channeled to communicate with said milk-port permanently and with said air-inlet and air-exhaust ports when moved there-over, but such channel being adapted to be 45 shut off from either of the latter ports when in communication with the other port, and means for moving said pulsator-valve to and 50 fro past said ports.

7. In a milking machine, in combination, a milk-receptacle, means for exhausting the same, a pulsator having an upright cylinder which opens at its lower end into said receptacle, a grooved valve movable up and down in said cylinder, the cylinder having an air-inlet and a milk-outlet in occasional communication with a groove in the valve when the latter is moved up or down, a valve in 55 said milk-port, a perforated vessel in said receptacle connected to the valve in said milk-port, removable means for balancing said vessel when empty to poise it in position to cause said valve to shut off said milk-port, 60 said vessel being located suitably in said re-

ceptacle to receive the entering milk and discharge the milk received therein through its said perforation more slowly than it is received, and means for moving said pulsator-valve up or down.

8. In a milking machine, in combination, a milk-receptacle, means for exhausting the same, a pulsator-cylinder having a milk-port, an air-inlet port and an air-exhaust port, the air-exhaust-port being in occasional communication with said receptacle, a movable valve in said cylinder having a channel adapted for occasional separated communication with said air-inlet and said air-exhaust port and for permanent communication with 70 said milk-port, a valve-chamber intersecting said milk-port, a movable valve in said valve-chamber adapted to shut off said milk-port when moved upwardly, an open vessel in said receptacle perforated at the base suspended from said cut-off valve, the perforation in said vessel being adapted to discharge milk received from said milk-port less rapidly than such milk is received from the port, a pivoted lever having a removable slideable 75 weight on its free end adapted to balance the weight of said vessel, the other member of said lever being pivotally connected to said cut-off valve, and means for causing a regular reciprocation of said pulsator-valve.

9. In a milking machine, in combination, a milk-receptacle, means for exhausting the same, a pulsator-cylinder opening into the milk-receptacle, said cylinder being provided on each side with an air-inlet port, an air-exhaust port and a milk-port, the said ports on one side being separated from the ports on the other side and independent therefrom, a pulsator-valve movable up and down in said cylinder and provided with a longitudinal 100 channel on each side in line with the said ports on each side and adapted when moved up and down to cause occasional communication between each channel and the air-inlet and air-exhaust ports on the same side, but 105 not to be in communication with either when in communication with the other, said channels being in permanent communication with the inner end of the milk-port on the same side, means for moving the said pulsator-valve upward to return by gravity, 110

a plunger-valve intersecting each of said milk-ports, said valve having a transverse channel adapted to register with said milk-port when the valve is at its lower position, and said valve being adapted to cut off said milk port when in its upper position, a vessel in said milk-receptacle suspended from each plunger-valve and adapted to receive milk from the milk-port thereabove and discharge it into 115 said receptacle, each vessel having a milk-exit adapted to discharge the milk therethrough more slowly than such milk is deposited in the vessel, and balancing-means 120 connected with each of said vessels and 125 130

valves adapted to cause the vessels to rise when emptied of milk to cause the valves to shut off the milk ports.

10. In a milking machine, in combination, a milk-receptacle, means for exhausting same, a pulsator-cylinder opening into said milk-receptacle, a pulsator-valve adapted to move up and down in said cylinder, a pivoted lever having one member pivoted to said pulsator-valve at the top, an electro-magnet suspended from the other member of said lever to balance said valve and being in circuit with some source of electrical power, a fixed armature opposite the poles of said electro-

magnet to which said magnet may be drawn 15 when the circuit is completed through it to lift said valve, and a circuit-interrupter adapted to regularly and periodically interrupt said circuit to cause said magnet to move to its balanced position and thus reciprocate the pulsator-valve.

Signed at Waverly, Iowa, this 6 day of May, 1908.
